ADDRESSING MACHINE

Carl J. Hueber, Euclid, and Arthur W. Oatess, Cleveland,
Ohio, assignors to Addressograph-Multigraph Corpora-
tion, Wilmington, Del., a corporation of Delaware

Application April 20, 1954, Serial No. 30,102

Term of patent 14 years

(Cl. D64—11)

FIG. 1

Des. 175,168

PAGE 2

FIG. 2

FIG. 3

Fig. 1 is a front perspective view of an addressing machine showing our new design;

Fig. 2 is a front elevational view thereof; and

Fig. 3 is a right side elevational view.

The side of the machine opposite that shown in Figs. 1 and 3, respectively, is substantially the same in appearance as the side shown.

We claim:

The ornamental design for an addressing machine, substantially as shown and described.
